(57) **CLAIM**

We claim the ornamental design for a display screen or portion thereof with graphical user interface to facilitate transfer of consideration between individuals in a common geolocation, as shown and described.

DESCRIPTION

The sole FIGURE is a view of a display screen or portion thereof with graphical user interface to facilitate transfer of consideration between individuals in a common geolocation. The outermost broken lines show a portion of the display screen and form no part of the claimed design. The remaining broken lines illustrate portions of the graphical user interface that form no part of the claimed design.
